UNITED STATES PATENT OFFICE.

WILLIAM C. LAWRENCE, OF TORRINGTON, CONNECTICUT.

BRICKLAYER'S TROWEL.

Application filed April 5, 1922. Serial No. 549,711.

To all whom it may concern:

Be it known that I, WILLIAM C. LAWRENCE, a citizen of the United States, and a resident of Torrington, county of Litchfield, 5 and State of Connecticut, have invented certain new and useful Improvements in Bricklayers' Trowels, of which the following is a specification.

This invention relates to bricklayers' or 10 masons' trowels and more particularly to a combined trowel and level.

One object of the invention is to provide 15 a device of this nature whereby a bricklayer or mason may quickly determine whether a brick is horizontal without requiring the use of the "long" level commonly employed.

A further object is to provide a combined 20 trowel and level having a leveling device mounted in the handle thereof.

A further object is to provide a device of 25 this nature which will be simple, strong, cheap to manufacture, and very efficient and durable in use.

With these and other objects in view, there 30 has been illustrated on the accompanying drawing one form in which the invention may be conveniently embodied in practice.

Fig. 1 represents a top plan view of a combined trowel and level embodying the principles of the invention.

Fig. 2 is a side view of the same.

Fig. 3 is an enlarged longitudinal sectional view taken through the end of the handle, 35 and showing the interior construction of the level.

In the ordinary process of building a brick wall, it is customary to lay the bricks in rows or courses having a layer of mortar 40 between adjacent rows. In order to insure that the bricks in each course are horizontal, the workman is required to make frequent use of a heavy "long" level. If the course of bricks is found out of level, the 45 workman must then manipulate each brick and the mortar under the brick to make it level. The bricklayer must alternately use his trowel and level until the row is correctly laid. This requires that the operator must 50 continually stoop down to pick up his heavy "long" level which naturally becomes fatiguing. Moreover, much time is often wasted in hunting for the "long" level as it sometimes becomes misplaced.

55 With the present invention, the above and other disadvantages have been practi-

ally avoided. This has been accomplished by providing a level in the handle of the trowel itself.

Referring now to the drawings in which 60 like reference numerals denote corresponding parts throughout the several views, the numeral 10 represents a blade having a flat bottom surface and formed in substantially the shape of a diamond. The blade 10 is 65 provided with a pair of slightly curved forward sides 11 and 12 terminating in the tip 13, and a pair of straight rear sides 14 and 15. At the rear of the blade and integrally formed therewith, there is an enlarged vertical shank 16 curved over backwardly and terminating in an upwardly inclined handle section 17 upon which is mounted a handle 18 preferably constructed of wood. The handle is held in place upon the shank 17 in 70 any suitable manner, and its lower end is protected by a metal ferrule 19.

A rectangular cavity 20 is formed in the top of the handle within which an elongated level glass 21 is firmly embedded by means of 80 plaster of Paris or any other suitable material 22. This level glass 21 which is substantially cylindrical in shape, is provided with a slightly rounded top 23 and is adapted to contain a sufficient amount of alcohol 85 or other suitable liquid to leave a bubble 24 as is usual in spirit levels. A cover plate 25 having a rectangular opening 26 is secured to said handle with its opening in alignment with the top of the level, by means 90 of the screws 27 and 28. These screws 27 and 28 are preferably provided with flat heads which are countersunk into the cover plate 25.

In operation, as each brick is laid upon the mortar, it may be tested by placing the blade of the trowel upon it, and thus if any brick is found to be out of level, it may be immediately corrected without loss of time. The trowel may also be laid upon several 100 adjacent bricks and in this way one may readily determine whether the last laid brick is in alignment with those previously laid.

When using the trowel, the operator may 105 exert force upon the blade to cause the bricks and mortar to become horizontal at the same time that he employs it as a level.

In some cases, with highly skilled workmen, a course of bricks may be laid with a 110 trowel made according to this invention without the use of the "long" level. In the

ordinary case, however, a bricklayer will not entirely dispense with the "long" level, but will use it less often than would formerly be required.

5 One advantage of this invention is that it materially saves the time of the bricklayer, as it reduces to a considerable extent the number of times he has to employ the regular "long" spirit level.

10 A further advantage is the greater accuracy and increased speed with which the bricks may be properly laid.

15 A still further advantage is that it enables an unskilled workman to lay bricks with greater speed and more correctly than a more experienced man without the use of this improved level-trowel.

20 While there has been disclosed in this specification one form in which the invention may be embodied, it is to be understood that this form is shown for the purpose of illustration only, and that the invention is not to be limited to the specific disclosure but may be modified and embodied in va-

rious other forms without departing from 25 its spirit. In short, the invention includes all the modifications and embodiments coming within the scope of the following claims.

Having thus fully described the invention, what is claimed as new, and for which it 30 is desired to secure Letters Patent, is:

1. A bricklayer's trowel comprising the combination with a blade for manipulating the mortar and bricks, of a shank connected to said blade, and a handle mounted on said shank, said handle having a level mounted therein to indicate when the blade is horizontal, whereby the bricklayer will be enabled when laying the bricks or smoothing the mortar to determine whether the work 40 is properly done.

2. In a bricklayer's trowel, a flat metal blade, a handle for said blade, and a level mounted in said handle for indicating when said blade is horizontal.

45 In testimony whereof, I have affixed my signature to this specification.

WILLIAM C. LAWRENCE.
